H. C. KARST

THUMB TACK

Filed Jan. 16, 1928

INVENTOR:

HOWARD C. KARST,

BY
Wedensky & Baird, Inc.
ATTORNEYS.

UNITED STATES PATENT OFFICE.

HOWARD C. KARST, OF PHILADELPHIA, PENNSYLVANIA.

THUMB TACK.

Application filed January 16, 1928. Serial No. 247,247.

My invention relates to a new and useful thumb tack whereby objects may be fastened to a support without being pierced or otherwise damaged.

5 My invention relates more particularly to a thumb tack of this general character adapted for firmly and detachably securing cards, Bristol board, drawing paper and similar objects to a drawing board, wall or 10 other support.

My invention further relates to a thumb tack which is adapted to be permanently engaged with a support if so desired, it being at the same time possible to employ said tack for fastening a variety of objects successively without the necessity of removing or disengaging said thumb tack from said support.

In thumb tacks known and used heretofore, it has been the practice to provide a stamping or head member having a central prong which is adapted to pass through the object to be supported and through the support. To avoid piercing the object being secured by the prong of the thumb tack, resort was had to a thumb tack having an elongated head portion and having the prong thereof positioned at one extremity of said head portion, the frictional engagement

20 of said head portion with object to be secured or its pressure against the support into which the prong of the thumb tack has been driven being relied upon to secure the object to the support. In all of these constructions it is necessary completely to disengage the thumb tack from the support when the object secured thereby is to be removed or replaced. Furthermore, the mere pressure of the head piece of the thumb tack 25 on the object inserted between it and the support or its frictional engagement with such object as the case may be, have frequently been inadequate, resulting in slipping and displacement of the object being secured.

To overcome these disadvantages and at the same time to provide a thumb tack which can be successfully employed for firmly and detachably securing objects to a 30 support without piercing or in any way damaging such objects I have provided a thumb tack consisting of an elongated head piece formed of spring metal and having a

central depression therein, so that when pressure is applied to the central depressed 55 spring portion of said head piece one end thereof will snap upwardly thus permitting the insertion of an object thereunder, said end being adapted to be snapped back downwardly into a tightly clamping position over 60 said object, the other end of said head piece being provided with prongs for engaging a suitable support to which it is desired to secure said object.

My invention further consists of the various novel features hereinafter described and claimed.

In the accompanying drawings:

Figure 1, represents a perspective view of a thumb tack embodying my invention. 70

Figure 2, represents a section on line 2-2 of Figure 1.

Figure 3, represents a sectional view of my novel thumb tack in the process of application. 75

Figure 4, represents a similar view showing my novel thumb tack in the engaging position.

Figure 5, represents a perspective view of a modified form of my invention. 80

Figure 6, represents a plan view of a further modified form of my invention.

Figure 7, represents a side elevation of Figure 6.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described. 85 90 95

Referring to the drawings, in which like reference characters indicate like parts. 1 designates a thumb tack embodying my invention comprising the body portion 2 formed of spring metal and having the peripheral prongs 3. The body portion 2 is composed of the slightly curved or convexed portions as 4 and 5 and is provided with the central recessed spring portion 6. The 105 prongs 3 are stamped from either end of the

body portion 2 as will be seen from Figs. 1 to 4 inclusive. 7 designates a suitable support such as a drawing board, wall or the like, on which it is desired to secure the sheet of paper, drawing card or other object 8. The operation of my novel thumb tack is as follows: The prongs 3 of the thumb tack 1, are driven into the drawing board or other support 7 by pressing on the portions 5 and 6 of the head or body portion 2 of the tack 1. The pressure exerted on the portions 5 and 6 to drive the prongs 3 into the support 7 causes the free end 4 to snap upwardly out of contact with the support 7, as is clearly shown in Fig. 3. This is due to the presence of the spring recessed portion 6, the general curvature or warping of the body portion 2 and the springy character of the metal from which it is made. The edge of the paper card or other object 8 is then inserted under the raised portion 4 and the latter is then pressed downwardly over the edge of the object 8 whereupon, due to the novel construction just recited it snaps downwardly into a tightly clamping position over the edge of the object 8 as is clearly seen in Fig. 4. It will be noted that the recessed spring portion 6 lies substantially flat on the surface of the support 7 while the free end 4 is in the raised position and that said portion 6 occupies a raised or arched position when the portion 4 is in the lower clamping position (see Fig. 4), in which position the spring metal body portion 2 as a whole is so warped or "cramped" as to exert considerable pressure on the object 8 clamped under the portion 4. To withdraw or remove the object 8 it is merely necessary to press downwardly on the raised or arched spring portion 6 (see Fig. 4) whereupon the clamping end 4 snaps upwardly into the raised position thus freeing the object 8 (see Fig. 3). It will now be apparent that my novel thumb tack serves efficiently and tightly to clamp an object 8 to a support 7 without in any way piercing or damaging such object. Furthermore, when objects of uniform size are to be successively secured to a given support, it will be entirely unnecessary to disengage the thumb tacks 1 from said support since it is only necessary to press on the recessed spring portion 6 to raise the clamping portion 4 and remove the object thus freed whereupon another object of substantially equal dimensions is positioned on the support 7 and the end portions 4 of the respective thumb tacks employed are pressed down into their clamping positions over the edges of said object as above explained. This not only eliminates the often rather irritating task of pulling out and driving in thumb tacks whenever it is desired to change or remove the drawing card or other object 8, but greatly increases the life of the drawing board or other support 7 (such as a wall or

the like) since it reduces to a minimum the number of holes or punctures made in such support.

In Figure 5 I have shown a modified form of my invention wherein I provide the body portion 2 on its underside with the bottom lugs 9 intermediate the recessed portion 6 and the prongs 3, said lugs being intended to facilitate the upward and downward snapping of the clamping portion 4. 75

In Fig. 6 I have shown a further modified form of my invention wherein the body portion 2 of the thumb tack 1 is provided with the rounded corners 10 and wherein the prongs 3 are stamped out from either of the portions 4 and 5 as at 11, it being understood that the opening left by the stamping out of these prongs may be closed by swaging the metal on either side of said opening. 80

The operation of the devices illustrated in Figs. 5 to 7 inclusive is the same as that set forth in connection with the other figures of the drawings and hence need not be described.

By providing a plurality of prongs 3 the thumb-tack 1 is prevented from rotation and its engagement with the support 7 is further improved. 85

It will now be apparent that I have devised a novel thumb tack whereby an object may be firmly and detachably secured to a support without being pierced by the prongs of said thumb tack and whereby an object thus secured may be withdrawn and replaced without the necessity of disengaging said thumb tack from said support, the working principle of my invention being the provision of an arched, warped body portion or head having a central spring recessed portion and provided at one end thereof with prongs for engaging a support, the other end of said body portion being free and adapted to snap upwardly away from said support when said spring recessed portion is in contact therewith and to be snapped downwardly into a tightly clamping position against support when the pressure on said recessed spring portion has been relieved. If desired, I might provide the underside of the outer edge of the portion 4 (see Fig. 5) with the teeth or serrations 12 105 for the purpose of more firmly gripping the object 8 being secured by this modified form of thumb tack. 110

Similarly, I may provide the underside of the outer edge of the portion 4 (see Fig. 7) 120 with the pendant flange 13 which serves to take up some of the room between the portion 4 and the board 7 more tightly to clamp the object 8 therebetween as will be apparent. 125

I am aware that the invention may be embodied in other specific forms without departing from the spirit or essential attributes thereof, and I therefore desire the present embodiment to be considered in all 130

respects as illustrative and not restrictive, reference being had to the appended claims rather than to the foregoing description to indicate the scope of the invention.

5 Having thus described my invention what I claim as new and desire to secure by Letters Patent, is:—

10 1. In a device of the character stated, a head piece formed of spring metal having a central, offset portion, one end of said head piece being provided with prongs adapted to engage a support and the other end thereof being adapted to be snapped towards and into a clamping position against said support to secure an object thereto, and to be snapped away from said support by the exertion of pressure on said central, offset portion to release said object.

15 2. In a device of the character stated, a generally elongated head piece formed of spring metal and having central, offset spring portion, one end of said head piece being provided with prongs adapted to engage a support and the other end thereof being adapted to be snapped towards and into a clamping position against said support to secure an object thereto, and to be snapped away from said support by the exertion of pressure on said central offset spring portion to release said object.

20 3. In a device of the character stated, a generally elongated, convex head piece formed of spring metal and having a central, offset, spring portion, one end of said head piece being provided with prongs adapted to engage a support and the other end thereof being adapted to be snapped towards and into a clamping position against said support to secure an object thereto, and to be snapped away from said support by the exertion of pressure on said central offset

25 spring portion to release said object.

30 4. In a device of the character stated, a generally elongated, convex head piece

formed of spring metal and having a central, offset spring portion, one end of said head piece being provided with prongs adapted to engage a support and the other end thereof being adapted to be snapped towards and into a clamping position against said support to secure an object thereto, and to be snapped away from said support by the exertion of pressure on said central, offset, spring portion, to release said object and means intermediate said offset portion and said prongs for spacing said head piece from said support.

35 5. In a device of the character stated, a generally elongated, convex head piece formed of spring metal and having a central, offset spring portion, one end of said piece being provided with prongs adapted to engage a support and the free end thereof being adapted to be snapped towards and into a clamping position against said support to secure an object thereto, and to be snapped away from said support by the exertion of pressure on said central offset, spring portion, to release said object means intermediate said offset portion and said prongs for spacing said head piece from said support, and means on the underside of the outer edge of said free end for engaging the upper surface of said object.

40 6. In a device of the character stated, a head piece formed of spring metal and having a central, offset spring portion, one end of said head piece being adapted to be secured to a support and the other end thereof being adapted to be snapped towards and into a clamping position against said support to secure an object thereto, and to be snapped away from said support to release said object, by the exertion of pressure on said central, offset portion, and means for spacing said head piece from said support.

HOWARD C. KARST.
